ILLUMINATED SIGN

William H. Harrington and Arvid H. Nero, West Hartford, Conn., assignors to The Arrow-Hart & Hegeman Electric Company, Hartford, Conn., a corporation of Connecticut

Application March 30, 1933, Serial No. 663,594

3 Claims. (Cl. 40—132)

This invention relates to illuminated signs. More particularly it relates to illuminated house numbers which are adapted to be permanently installed within a recess or an outlet box in the wall of a house or building.

It is an object of our invention to provide an illuminated sign which may be inexpensively manufactured and easily installed.

Another object of our invention is to provide an illuminated house number in which the desired number may be made up from preformed interchangeable stencils or the like.

Another object of our invention is to provide a self-contained bodily removable sign unit which may be assembled separately from the remainder of the device and later assembled with the remainder of the device.

Other objects and advantages of our invention will become apparent as it is described in connection with the accompanying drawings.

In the drawings:—

Figure 1 is a plan view of one form of our invention, completely assembled.

Figure 2 is a rear view of the construction shown in Figure 1 with portions of the device broken away for the purpose of illustration.

Figure 3 is a plan view of the sign unit which is used in the construction shown in Figure 1. In this figure portions of the unit are broken away for the sake of clearer illustration.

Figure 4 is a plan view of the base and socket construction upon which the face plate and sign unit visible in Figures 1 and 3 may be mounted.

Figure 5 is a section view taken on line 5—5 of Figure 1.

Figure 6 is a plan view of a modified form of our invention. In this view portions of the device are broken away for the purpose of illustration.

Figure 7 is a transverse section view taken on line 7—7 of the construction shown in Figure 6.

Referring to the drawings, a base 10 of insulating material, preferably white such as porcelain, is provided with an open cavity 12 in which is positioned an electric lamp 14 whose screw-shell base 16 engages with a conventional ring-type, socket-member 18 which is secured to the base 12 and has a wire terminal 20. The center contact of the lamp base engages with a metallic conductor 22 which is secured to the base 12 and has a wire terminal 24. Supporting ears 26 of conventional form are provided on opposite sides of the base and in order that the base may be secured in a wall cavity or outlet box according to common practice. Lying over the top of the

base 10 and covering the cavity 12, is a face plate 30 which may be stamped from sheet metal or made of molded insulating material according to conventional practice, and provided with a centrally located rectangular aperture 31 behind which is positioned a sign unit hereinafter more particularly described. The face plate 30 may be secured to the supporting ears 26 by screws 32, and these screws may also serve to hold the sign unit between the face plate 30 and the base 12. The metal around the apertures for screws 32 is preferably extruded toward the back of the plate thus, at once, providing for counter sinking the screw heads and providing protuberances 33 to assist in the positioning of the sign unit behind the aperture in the face plate as will hereinafter more fully appear.

Referring to Figure 3 it will be noted that the sign unit is formed of two metallic mounting plates 36 and 38 approximately equal in size and each having a rectangular aperture in its center which is adapted to register with the aperture 31 in the face plate 30. One of these plates (the outer plate 38 in the form as illustrated in Figure 5) may have four lateral extensions or tongues 39 which are able to be bent over the other plate (the inner plate 36) to hold the two plates together. To keep the mounting plates 36 and 38 from slipping upon one another when the tongues 39 are located at the ends of plate 38, the plate 36 is cut away adjacent the tongues 39 forming shoulders 41. As illustrated, the plate 36 has provided around its central aperture, which is slightly larger than the aperture in plate 38, offset portions or marginal flanges 40 to receive light-pervious sign means which will now be described.

The light-pervious sign means is held between the mounting plates 36 and 38. The means comprises a plate 46 of translucent white glass of rectangular shape, being in size slightly larger than the aperture 31 in the face plate 30 but small enough to fit within the flanges 40. This plate presses against the bottoms or inturned portions of the flanges. It serves to diffuse the light from the lamp 14. Lying against or next to the translucent plate is an opaque stencil 44 of cardboard, fibre or other suitable material. This stencil may be made up of a plurality of panels 44a to 44e, some of which have numerals cut through them so that any desired number whether of one, two, three or four digits may be readily made up. If the number consists of less than four digits, blank panels like 44a and 44e may be provided at the ends of the stencil. It will be apparent that other designs than numerals may

be cut through the stencils to appear in silhouette. Alternately, the design may be opaque allowing the light to shine around it forming a background. Lying against the stencil on the opposite side of it from plate 46 is a transparent glass plate 42 which serves to keep dirt from the stencil. Obviously the plates 42 and 46 need not be made of glass but may be made of any light-pervious material. The stencil also may be somewhat light-pervious, though the construction shown is preferred. It is also within the view of this invention to have the number or design painted upon either the translucent or transparent plate. The plates 36 and 38 each have a pair of holes 49 on each side of the central aperture which register with each other and with the holes in the face plate through which the screws 32 pass. The holes in the plates 36 and 38 are large enough to accommodate the extrusions 33 of the face plate so as to position the sign unit behind the face plate as hereinbefore indicated.

From the foregoing it will be observed that the translucent and transparent plates 46 and 42 respectively and the stencil 44 or design means 44 may be inserted in the offset portion of the plate 36 and then the plate 38 placed upon them and the tongues 39 bent over to hold all of these parts together to form a self contained, bodily movable unit.

Referring now to Figures 6 and 7 it will be noted that the construction shown therein is substantially the same in principle as that just described, but since the form shown in Figures 6 and 7 is smaller, for numbers having no more than two digits, a smaller insulating base 110 is provided for the electric lamp, and it is supported on a U-shaped supporting strap 115. The construction of this lamp holder is well known from its use in the art behind pilot or warning light devices, and it need not be described in detail herein.

The sign unit in Figures 6 and 7 differs from the sign unit shown in Figure 3 in the respect that the plate 38 is omitted. The transparent and translucent members 142 and 146 respectively and the stencil which is located between them are held in the offset portion or flange 140 of the mounting plate 136 by reason of the engagement of the face plate 130 with the mounting plate. The mounting plate 136 is positioned behind the aperture 131 in the face plate by means of extrusions like the extrusions 33 in Figures 2 and 5 in

the same manner as was described in connection with Figures 1 to 5.

In both of the forms of the invention described moisture may be excluded from the sign by the provision of a rectangular rubber sheet or gasket 50 (Figs. 1-5) or 150 (Figs. 6-7) between the base 10 (or 110) and the mounting plate 38 (or 138). To permit the light from the electric lamp to penetrate the sign means this rubber sheet must be provided with an opening at least as large as the opening in the face plate. The sheet will be, in size, slightly larger than the plates 30 and 130 respectively. This rubber sheet will be held in position by the same screws 32 which hold the face plate and sign unit to the base.

Many modifications and changes within the scope of our invention may be devised by those skilled in the art, therefore we do not limit ourselves to the construction shown.

We claim:

1. An illuminated sign comprising an insulating base having an electric lamp socket, an apertured face plate, means to secure said plate to said base and a sign carrying device secured between said plate and base, said sign device comprising a pair of parallel apertured plates one of which has tongues bent over the other to hold said plates together, and one of said parallel plates having flanges receiving a translucent sheet, a transparent sheet and a stencil and holding them between said parallel plates, the same means which holds said face plate also holding said sign device in position.

2. An illuminated sign comprising an insulating base containing an electric lamp socket, a face plate, means to secure said face plate to said base, and a sign-containing unit held between said plate and said base by said means, said unit having an offset portion, a translucent member, a transparent member and a plurality of interchangeable stencils seated in said offset portion.

3. An illuminated sign comprising an insulating base containing an electric lamp socket, a face plate, means to secure said face plate to said base, and a sign-containing unit held between said plate and said base by said means, said unit having an offset portion, a light-pervious member, and a plurality of interchangeable stencils seated in said offset portion.
